IMPROVEMENT IN BAG HOLDERS.

J. V. HENRY NOTT, OF GUILDERLAND, NEW YORK.

Letters Patent No. 60,233, dated December 4, 1866.

SPECIFICATION.

TO ALL WHOM IT MAY CONCERN:

Be it known that I, J. V. HENRY NOTT, of Guilderland, in the county of Albany, and State of New York, have invented a new and improved Bag Holder; and I do hereby declare that the following is a full, clear, and exact description thereof, which will enable others skilled in the art to make and use the same, reference being had to the accompanying drawings, forming a part of this specification.

The present invention relates to a new and useful device for holding the mouth of a bag open while being filled, whereby it can be filled with readiness and despatch; and it consists in arranging upon an upright post or standard a frame consisting of two similar bent or curved horizontal spring arms, both having their upper edge made with an outward projecting lip or flange, and attached to a common centre-piece or collar placed over said post, and sliding loosely thereon, over the flanges of which arms, across from one to the other, the edge of the mouth of the bag is placed by bringing or bending the two arms toward each other; when, releasing them, they immediately spring apart, drawing and holding the mouth of the bag tightly on and between them, and sufficiently open to enable the bag to be filled with the utmost convenience and ease; the said bag-holding frame being also so arranged upon the post or standard provided for it that it can be adjusted and set at any desired height thereon, according to the length of the bag which is to be held by it to be filled.

The figure in the accompanying plate of drawings represents my invention, and is a perspective view of my improved bag holder, with a bag suspended or hung upon it; the bag holder, for the purpose of illustrating, being shown as arranged or placed upon a suitable base or platform A. This base is mounted on rollers or casters, so that it can be freely moved about from one place to another, and has extending from it an upright post or standard B, over which, by its collar or sleeve portion C, is placed my bag-holding frame D, consisting of two similar horizontally bent or curved spring arms F, which, together, form a semicircle, or nearly so. Each of these arms, F, is provided with an outward projecting lip or flange a along their upper edges, over each of which the opposite sides of the edge of the mouth of the bag G is lapped or placed, when the holder is to be used, by bringing or bending the said arms in and toward each other; when, releasing them, they immediately spring apart or open, as it were, tightly drawing and holding the mouth of the bag on and between them, as is obvious, and sufficiently open to enable it to be filled with the utmost facility and convenience. The frame D, by its sleeve C on the post, may be fastened at any desired height by means of a set-screw properly applied to it therefor; but in order to facilitate and simplify its adjustment, and make it self-fastening, I form a series of notches, d d, at the upper portion of the post B, and upon its side, from which the frame extends, with which notches, by the gravity of the frame and the bag hung or suspended from it, the lower edge of the sleeve portion of the frame engages, and is there so held until released, by raising the frame sufficiently therefor, as is manifest without further explanation; the particular notch with which the bag-holding frame is so engaged depending upon the height at which it is desired to have the mouth of the bag, and according to the length of the same. For convenience of transportation of the bag holder, the post B may be mortised in the base A, or in any other proper manner attached to it, so that it can be detached at pleasure.

I claim as new, and desire to secure by Letters Patent—

The frame D, consisting of two bent or curved spring arms F, each having an outward projecting lip or flange, in combination with the post or standard B, when arranged together, so as to operate substantially in the manner described, and for the purpose specified.

J. V. HENRY NOTT.
